(57) **CLAIM**

The ornamental design for a computer mouse, as shown and described.

DESCRIPTION

FIG. 1 is a perspective view of a computer mouse showing the novel design;

FIG. 2 is a top view thereof;

FIG. 3 is a bottom view thereof;

FIG. 4 is a side view thereof;

FIG. 5 is a front view thereof; and,

FIG. 6 is a back view thereof.

The broken lines shown in FIG. 3 represent portions of the computer mouse that form no part of the claimed design.
